(57) **CLAIM**

The ornamental design for footwear, as shown and described.

DESCRIPTION

FIG. 1 is a top, right perspective view of footwear showing the new design;

FIG. 2 is a bottom, right perspective view thereof;

FIG. 3 is a top, left perspective view thereof;

FIG. 4 is a bottom, left perspective view thereof;

FIG. 5 is a front elevation view thereof;

FIG. 6 is a rear elevation view thereof;

FIG. 7 is a right side view thereof;

FIG. 8 is a left side view thereof;

FIG. 9 is a top plan view thereof; and,

FIG. 10 is a bottom plan view thereof.

The dot-dash lines illustrate the boundary of the claimed design and form no part thereof. The portions of the figures outside of the dot-dash line shown in lighter contrast illustrate other portions of the footwear and form no part of the claimed design. The dash-dash, broken lines show portions of the footwear that form no part of the claimed design.
